United States Patent

Des. 241,434
Patented Sept. 14, 1976

241,434

BALL POINT PEN

Richard Schenk, 933 Knollwood Road,
White Plains, N.Y. 10603

Filed Apr. 16, 1975, Ser. No. 568,414

Term of patent 14 years

Int. Cl. D19—06

U.S. Cl. D19—49

FIG. 1

FIG. 5

FIG. 2

FIG. 3

FIG. 4

FIG. 1 is a perspective view of a ball point pen showing my new design;

FIG. 2 is a front elevational view showing the cap positioned on the end remote from the writing point;

FIG. 3 is a bottom plan view of FIG. 1;

FIG. 4 is a top plan view thereof; and

FIG. 5 is a left side elevational view of FIG. 2.

I claim:

The ornamental design for a ball point pen, as shown and described.
